UNITED STATES PATENT OFFICE.

LEAH G. MILKES, OF MINNEAPOLIS, MINNESOTA.

CATAMENIAL APPLIANCE

1,108,206.

Specification of Letters Patent. Patented Aug. 25, 1914.

Application filed March 27, 1914. Serial No. 827,614.

To all whom it may concern:

Be it known that I, LEAH G. MILKES, a citizen of the United States, residing at Minneapolis, in the county of Hennepin and State of Minnesota, have invented certain new and useful Improvements in Catamenial Appliances; and I do hereby declare the following to be a full, clear, and exact description of the invention, such as will enable others skilled in the art to which it appertains to make and use the same.

My invention is directed to the provision of a simple, sanitary and efficient catamenial appliance, in the nature of a double protector or combined apron and napkin holder.

Generally stated, the invention consists of the novel devices and combinations of devices hereinafter described and defined in the claims.

20 In the accompanying drawings, like letters indicate like parts throughout the several views.

Referring to the drawings: Figure 1 is a perspective view showing the complete appliance applied as worn; Fig. 2 is a perspective view looking at the appliance from the rear, some parts being broken away; Fig. 3 is a section taken on the line a^3-a^3 of Fig. 4; Fig. 4 is a perspective view looking at the 25 appliance from the front and side; and Fig. 5 is a perspective view showing the pad removed from the apron.

The apparatus comprises two main elements, to-wit, an apron 1 and a napkin holder 2, both of which are preferably made chiefly from flexible waterproof material such as rubber cloth. The apron 1, however, preferably has an upper portion made of suitable netting indicated at 1^a, to make the 30 apron cooler to the wearer. The apron 1 is attached to a waist band 3, the ends of which are adapted to be tied in front. The napkin holder has cross loops 4, under which the absorbent napkin 5 is adapted to be passed.

45 On its rear end, the napkin holder 2 has tabs 6 that are adjustably and detachably secured to tabs 7 on the apron 1, by means of separable fasteners 8, of the glove fastener type. The tabs 7 are preferably extended across and stitched to the network 1^a, so that connections are thereby made with the back of the waist band 3.

To the front end of the holder 2, elastic straps 9 are attached. The free ends of the

straps 9 are equipped with coöperating fasteners or interlocking devices 10, one of which should be adjustable on the strap to which it is secured, so as to thereby make the appliance adjustable.

Attached to straps 9 of the napkin holder, 55 at points near to the fastener 10, where they will come at the back of the wearer, are depending tabs 7^a having the same fastener elements 8, as have the tabs 7 of the apron, so that the pad holder may be adjusted, as 60 shown in Fig. 5, and worn, at night, or at any other time, independently of the apron.

Above its lower edge, the apron 1 has a reinforcing strip 11, to which the upper ends of hose supporting straps 12 are attached.

In Fig. 1, the numeral 13 indicates an ordinary corset having hose supporting straps 14. The manner of applying the device is obvious, and is illustrated in the drawings. The hose supporters 12 on the apron, not 70 only support the hose, but keep the apron pulled down and properly and smoothly held in position. The napkin holder is attached and, in part, supported from the apron, but is adjustable in respect thereto. 75 The napkin holder can be removed from the apron, and the apron can then be worn under evening gowns and supper dresses. The appliance when used complete, affords a double protection, and is sanitary and capable of being easily laundered.

What I claim is:

1. In a device of the character described, the combination of an apron, a napkin-holder, separate and independent waist bands for securing said apron and front end of said napkin holder around the waist of the wearer, and means on the rear end of the napkin-holder for securing the same to said apron or to the waist band of the napkin-holder when said napkin-holder is worn without the apron.

2. In a device of the character described, the combination of an apron or skirt protector, a napkin-holder detachably and adjustably secured to the body of said apron, and separate and independent means for securing the said apron and napkin-holder around the waist of the wearer.

3. In a device of the character described, the combination of an apron, a napkin-holder detachably secured to said apron at its rear end, separate and independent waist

straps or bands for securing said apron and front end of said napkin-holder around the waist of the wearer and means on the rear end of said napkin-holder for securing the 5 same to said napkin-holder waist band when said napkin-holder is worn independent of the apron.

In testimony whereof I affix my signature in presence of two witnesses.

LEAH G. MILKES.

Witnesses:
